EXTRUDED ALUMINUM CHANNEL

Philip A. Greer, Lake Oswego, Oreg.
(Box 172, Alamo, Calif. 94507)

Filed Jan. 25, 1971, Ser. No. 109,743

Term of patent 14 years

Int. Cl. D25—01

U.S. Cl. D13—6

FIG. 1 is a perspective view of an extruded aluminum channel structure showing my new design;

FIG. 2 is a further perspective view of the aluminum channel structure; and

FIG. 3 is an end view thereof.

I claim:

The ornamental design for an extruded aluminum channel, as shown.
